(57) **CLAIM**

The ornamental design for an upper coolant housing for an engine as shown and described.

DESCRIPTION

FIG. 1 is a front, top perspective view showing my new design;

FIG. 2 is another top perspective view thereof;

FIG. 3 is another top perspective view thereof;

FIG. 4 is another top perspective view thereof;

FIG. 5 is a top plan view thereof;

FIG. 6 is a front view thereof;

FIG. 7 is a rear view thereof;

FIG. 8 is a left-side view thereof; and,

FIG. 9 is a right-side view thereof.

The broken lines in the drawings illustrate portions of the upper coolant housing for an engine that form no part of the claimed design.
